UNITED STATES PATENT OFFICE.

GEORGE W. SWIFT, JR., OF BORDENTOWN, NEW JERSEY.

MACHINE FOR MAKING ONE-PIECE WINDOW ENVELOPES.

Application filed December 14, 1925. Serial No. 75,317.

The present invention relates to a machine for economically manufacturing window envelopes of the type in which an integral portion of the envelope material is made into a transparent address-disclosing window, by applying a coating of a suitable varnish or lacquer in the zone in which the window is to appear. This type of window envelope is known as a one-piece window envelope to distinguish it from the two-piece form of window envelope in which a patch of transparent paper is pasted over a cut-out opening in the material of the envelope.

Heretofore the one-piece window envelope has been produced either by imprinting and curing transparentizing coatings of lacquer or varnish upon envelope blanks, or sheets from which blanks are to be cut, and afterwards making up the envelopes in the ordinary way; or by taking made-up envelopes and imprinting and curing the transparentizing coatings upon the previously finished envelopes.

The present invention is an advance in the art of making single piece window envelopes resulting in a greater economy and a more uniform and superior product. The drying and curing oven is utilized to simultaneously dry the envelope adhesive and the imprints of transparentizing material. This is a feature of great importance and economy of cost and time over all methods heretofore employed in which the imprints of transparentizing material have invariably been dried and cured independently of the drying of the completed envelopes.

The present invention consists of a machine for making single piece window envelopes by a continuous process from a roll of envelope material which is passed through continuously operating mechanisms for imprinting the coating of transparentizing varnish or shellac, cutting out and pasting the seams of the successive blanks, folding and completing successive envelopes including the application of paste to the sealing flap and finally passing the completed envelopes to a drying chain which runs through a curing oven from which completed cured one-piece window envelopes are delivered.

In addition to this main feature of a continuous machine for successively performing the steps in the production of this type of window envelope, the present invention

also includes certain specific features of construction of some of the mechanisms for facilitating the desired result.

In the accompanying drawings I have illustrated one form of a machine embodying my invention for continuously manufacturing one-piece window envelopes.

In the said drawings:—

Figure 1 is a vertical longitudinal sectional view of the front portion of the improved envelope machine;

Figure 1^a is a similar view of the rear portion of the machine;

Figures 1 and 1^a taken together show a complete vertical longitudinal sectional view of the machine;

Figure 2 is a vertical transverse sectional view of the mechanism for imprinting patches of varnish or other transparentizing material upon the running web of envelope material;

Figure 3 is a plan view of the same;

Figure 4 is a vertical longitudinal sectional view of the same;

Figures 5, 6 and 7 are detail views illustrating parts of the same mechanism;

Figure 8 is a side elevation partly in section of the envelope forming mechanism and part of the endless drying chain;

Figure 8^a is a detail sectional view taken on line 8^a—8^a of Figure 8;

Figure 9 is a plan view of the same mechanism as shown in Figure 8;

Figure 10 is a vertical longitudinal sectional view of the same mechanism as shown in Figure 8;

Figure 11 is an enlarged detail vertical longitudinal sectional view showing the mechanism for transferring envelopes from the forming mechanism to the drying chain;

Figure 12 is a front view of the same mechanism.

The improved machine operates upon a continuous roll or web of paper which passes the continuously operating mechanisms for performing the successive steps in producing one-piece envelopes from a continuous web.

1 is a roll of a continuous web of envelope material journaled at 2 upon the side frames 3 which are mounted upon suitable legs or supports indicated at 4. The web 1 passes through suitable feed rolls 5 then around a take up roll 6 through the tension rods or rollers 7 and around the upper and lower rollers 8, 9. Between the rollers 8

and 9 the edges of the web are folded longitudinally and creased in passing around the roller 9.

The web passes up from roller 9 through 3 the male and female side seam cutters indicated at 10, 11 and from there under the adjustable compensating rolls 12 and over the lower guide roller 13.

The web with side flaps formed then 10 passes through a series of printing rolls indicated at 15, 16 and 17 which are arranged to print in three different colors if desired.

20 is a receptacle containing adhesive gum in which rotates the distributing 15 roller 21 which intermittently contacts with the cut-away gum roller 22, cooperating with the guide roller 23 for applying strips of gum to the under surface of the successive side flaps formed in the web. The 20 gum receptacle 20 is adjustably supported upon the rollers 25 having flattened faces which permit the gum receptacle to be lowered away from the gumming die.

From the side seam gumming device the 25 web passes around the guide rollers 30, 31, 32, 33 and 34 to present the reverse or upper face of the web to the action of the rotating pad or die which applies the imprint or coating of transparentizing material in a 30 manner which will now be explained.

35 is a boxlike reservoir supported at one end upon the transverse rail 36 and at its opposite end upon the adjustable rollers 37 having cut-away faces 38 and mounted upon 35 a transverse adjusting shaft 39 which is journaled in the side frames 3 and is provided on one end with an operating handle 40. A slotted arm 41 is adapted to move into and out of engagement with a threaded 40 bolt 42 passing outwardly through one of the side frames 3 and receiving an extended nut 43 by which the arm 41 can be clamped against the side frame for holding the shaft 39 and rollers 37 in position to support the 45 reservoir 35 in its normal operative position. This securing arm 41 and its screw clamp are of the same construction as that hereininafter described in connection with the sealing flap gumming device shown in Figure 8 50 of the drawings. The supporting rollers 39 have secured to their outer faces hooks 45 arranged to engage lateral pins or lugs 46 projecting from the side faces of the reservoir 35 for securely holding the reservoir in 55 its raised operative position.

A distributing roller 50 is journaled in the side frames of reservoir 35 and operates partly immersed in the composition varnish or shellac indicated at 51 which is employed 60 for forming transparent windows in the envelope material. The shaft of roller 50 projects through stuffing boxes indicated at 52.

A cover plate 55 mounted upon the reservoir 35 carries upwardly projecting brackets 65 56 in which are mounted journal bearings 57

supporting the shaft 58 of a die roller 59. The cover plate 55 has an opening to permit the periphery of distributing roller 50 to project into the path of the die carried by roller 59. 60 is a plate extending across the 70 cover plate 55 and carrying within the reservoir 35 a scraper blade 61 which operates in peripheral engagement with distributing roller 50. This plate 60 carries swivelled threaded nuts 65 projecting beneath its ends 75 in which engage the adjusting screw rods 66 rotatably mounted in the bracket arms 67 secured to the end of the reservoir 35. By turning the screw rods 66 the relation of scraper blade 61 to the roller 50 can be adjusted to suit the requirements.

The die roller 59 has removably mounted upon it a relatively soft gelatine or rubber pad 70 of the size and shape of the desired window in the envelope. Mounted upon the cover 55 at 75 is a spring blade 76 carrying at its upper end a scraper bar 77 which is supported in the path of the rotating pad 70. The guide roller 59 carries adjacent its ends the cams 80 which are adapted to engage the 90 ends of the scraper bar 77 and determine the moment of engagement of the scraper with the pad 70. In the first engagement of cams 80 with bar 77 the scraper bar will be held out of contact with the leading edge of the 95 pad 70, the cam faces gradually lowering so that the scraper will come in contact with the rear portion of the pad to remove the surplus of material from the pad.

It will be observed that the die roller 59 just described operates vertically between the guide roller 34 above referred to and the distributing roller 50 for the purpose of taking a film of transparentizing material from roller 50 and imprinting it upon the 105 running web of envelope material passing around the roller 34. Since the leading edge of the pad 70 is not engaged by the scraper bar 77 it will be understood that the first 110 contact with the running web will be with a film of the varnish which will be squeezed out upon the web and be equalized over the surface of the rear portion of the pad which is closely scraped by the engagement of the 115 bar 77. This arrangement has proven effective in avoiding the application of an objectionable quantity of the transparentizing varnish upon the web of envelope material.

It will be understood that when it is desired to throw out of action the die mechanism for imprinting transparentizing material upon the web, the rollers 37 are turned to present their flat faces towards the bottom of the reservoir 35, which will lower the reservoir and the die roller into inoperative position. It will be observed that the distributing roller 50 and die roller 59 are rotated by gearing driven from the shaft of roller 34, the die roller 59 rotating in unison with the roller 34.

From the guide roller 34 the web 1 having received the impression of transparentizing varnish passes to the envelope forming and completing machine or mechanism which may be of any suitable construction and in the drawings is shown of a general form illustrated in Patent No. 1,275,788, granted to me August 13, 1918. It will, however, be understood that this patent illustrates the other form of window envelope machine and that the envelope forming mechanism alone is similar to the structure embodied in the present application. Web 1 passes between feed rollers 90 which are so shaped as to avoid contact with the gummed and varnished parts of the web; thence between the shearing guides 91 whereby the web is sub-divided into separate envelope blanks; and thence to the feed rollers 92 having co-acting feed segments and on one of said rollers the guide-wires 92^a. From the feed rollers 92 the separated blanks pass to the control of the creaser and carrier roll 95 formed with a series of transverse notches in which are mounted gripper plates 96, 97. A rotary folder 98 cooperates with the carrier roll 95 to fold the successive blanks along lines which form the bottom of the envelopes. As each blank is creased in its bottom fold between members 95 and 98, the leading edge of the back portion of the envelope blank is projected beyond a fixed knife bar 110 with which cooperates a rotary knife blade 111 mounted on shaft 112. The knives 110 and 111 clip off the lower corners or tails of the blank. The bottom folded blanks are then carried through the side seam folders indicated at 99 to the folding roll 100 which creases the sealing flap. The folding roller 100 carries a gumming die 115 for applying gum to the sealing flap of the envelope as it passes. This gumming die 115 periodically contacts with a gum distributing roller 116 immersed in a suitable adhesive indicated at 117 contained in the reservoir 118. The reservoir 118 is adjustably supported upon the rollers 119 having cut-away faces 120 mounted upon a manually adjustable shaft 121. This shaft 121 carries a slotted arm 122 engaged by an adjusting nut 123 for clamping the shaft and supporting rollers in operative position. These rollers 119 carry hooks 124 which engage pins 125 upon the gum box 118. A roller 130 operates in peripheral engagement with distributing roller 116 for determining the quantity of an adhesive carried upon the surface of the material to the flap gumming die. This roller 130 is adjustably hung from the cover 137 of the gum box and is adjustable toward and away from the distributing roller 116 by manually operating threaded rods 135.

The complete envelopes then move past the lower wire guides 105 and upper wire

guides 106 to the two sets of delivery rollers 108, 108^a, 109, 109^a, which are spaced to avoid interference with the exposed patches of varnish and the gum surface of the sealing flap. The lower narrow faced wheels or rollers 108 are journalled upon trunnions and are connected by a curved segmental plate or platen α which rotates therewith and serves to support an envelope as it passes between rolls 108 and 108^a. The upper narrow faced wheels or rolls 108^a are mounted upon a shaft extending between them and each of the rollers 108^a is formed with a segmental cutout γ which provides leading gage face β with which the bottom edge of the envelope engages and registers to ensure the straightening of the envelope as it passes forward to delivery rollers 109, 109^a, and timing the delivery of envelopes to the drying chain. The curved supporting plate α is brought into action while the envelope is thus being registered under the cutout portions γ of the upper rolls 108^a. These final rollers pass the completed envelopes into a drying chain of grippers which carry them through a curing oven, the final delivery of envelopes to said chain being through the mechanisms which will now be described.

It is necessary in feeding the completed varnished envelopes to the grippers of the drying chain to avoid contacting between the projecting gummed sealing flaps of the envelopes and the imprints of transparentizing varnish. This has been successfully accomplished by providing devices for supporting the flap of each envelope in the chain out of the path of each succeeding envelope that is fed to the chain and also to cause the ends of the sealing flap to be tucked into and gripped by the grippers.

I prefer to employ an endless chain of envelope carrying grippers similar in construction and operation to that shown in Patent No. 864,493, granted to me August 27, 1907. This endless drying chain of grippers is represented in the drawing by the numeral 150 which passes around and is supported by a series of large carrying sprocket wheels 151, 152, 153, 154, 155, 156 and the smaller sprocket wheels 157, 158, 159, 160, 161. These sprocket wheels are suitably mounted in bracket supports of any suitable construction which it will not be necessary to describe in detail. The grippers shown best in Figures 9, 10 and 11 comprise lower spaced gripper fingers 165 rigidly attached to a base bar 166 having oppositely projecting ears 166^a and upper spaced movable gripper arms 167 united by an integral bar 168. The upper movable pair of grippers 167 is pivotally mounted upon the lower pair of gripper arms 165 by means of the pivot rods 169 which pass through the over-lapping ears 166^a and 168^a; said rods 169 connecting the grippers into an

endless chain and the projecting ends of the rods 169 travelling in the guideway of track bars 170. The movable gripper bar 168 has formed integral with one of its lugs 168^a a tappet finger 171 which is brought into contact with fixed cam 172 in the endless chain trackway for opening each pair of grippers as it reaches position to receive an envelope from the delivery rollers. A spring 175 surrounds each pivot rod 169 and engages at its opposite ends the fixed and movable gripper bars 166 and 168 for yieldingly retaining the grippers in closed position. The movable grippers have downwardly presented registering fingers 167^a to limit the movement of envelopes into the open grippers.

Referring to Figure 8^a it will be observed that the gripper fingers 165 and 167 are preferably formed with complementary concave and convex engaging faces; that is the face of one finger will be concave while the face of the cooperating finger will be convex so as to give a more reliable grip upon the ends of the envelope.

In addition to the wire guides 105 and 106 above referred to, I provide a series of wires 180, 181 adjustably mounted in a cross bar 182 and formed at their lower ends with upwardly and rearwardly bent guide portions approximately parallel with and above the path of travel of envelopes from folding roller 100 to delivery rollers 108. The central wire 181 carries an inclined guide-plate 185 supported centrally over the path of envelopes.

As each gripper of the drying chain reaches a horizontal position in the plane of delivery of rollers 109, 109^a, the gripper is opened by cam 172 and the envelope is delivered therein with the gummed sealing flap projecting downwardly therefrom as shown clearly in Figures 10 and 11 of the drawings. The gripper still in open position moves upwardly to place the succeeding gripper in open envelope receiving position and to avoid the projecting flap of the first envelope mentioned, dragging over the still moist imprint of varnish on the face of the next envelope, said preceding flap is engaged, pushed into the open gripper, and raised up out of the path of said next envelope. This important operation is accomplished by a blade 190 formed on the lower end of rod or wire 191 which is adjustably mounted in a rock shaft 192 and projects downwardly and inwardly to the central longitudinal plane of the machine. The rock shaft 192 is suitably journaled in bracket arms 193 and carries on one end a rock arm 194 connected with pitman 195 which is in turn connected by crank pin 196 with the shaft of the folding roller 100. This arrangement provides for an inward movement of the blade 190 for each envelope immediately after it has been placed in an open gripper.

In addition to the described action upon the sealing flap I provide rocking blades which are arranged to engage the sealing flap adjacent to its ends to tuck them into the bite of the gripper jaws. This device comprises the two blades 200 projecting from a rock shaft 201 journaled in brackets 202 to points just above the delivery rollers 109^a. These blades 200 will therefore be presented in the same vertical planes as the gripper jaws. The upper movable gripper jaws 167 are formed slightly longer than the lower fixed jaws so that upon the arrival of a pair of closed grippers with an envelope above delivery rollers 109^a, the blades 200 are moved upwardly by rocking shaft 201 with the result that the ends of the sealing flap will be engaged directly beneath the projecting ends of the upper grippers 167 and pressed upwardly against the envelope ends supported against said upper grippers, the upper grippers being thereby raised against the action of their spring so that upon the return movement of blades 200 the ends of the sealing flap will be found to be engaged with the envelope ends by the gripper jaws. This operation is clearly illustrated in Figures 10 and 11 of the drawings.

The rock shaft 201 carries at one end a rock arm 205 connected at its end with a pitman 206 having at its ends a guide yoke 207 which guides upon the projecting shaft of one of the rollers 91 above referred to. This roller carries upon its shaft a cam 208 which acts upon anti-friction roller 209 journaled upon pitman 206. A spring 210 extends between the pivot connection of members 205, 206 and a stationary point 211 to hold the blades 200 in normal retracted position and cause the pitman 206 to follow the actuating cam 208.

The drying chain is arranged to move in a zigzag path upwardly and downwardly through a drying and curing oven of which the hood or top portion is made up of suitable side walls 215, top wall 216 and the downwardly projecting end walls 217. The lower portion of the oven has the bottom wall 218, the shaped end wall 219 which is offset from end wall 217 to permit the passage of the drying chain at the entry side of the oven and the short end wall 220 with horizontal extension 221 arranged sufficiently below the guide rollers or sprockets 156 to permit the passage of the chain and envelopes adjacent the delivery end of the machine.

The oven may be heated by any suitable means such for instance as shown in which one or more perforated gas burner pipes 225 are mounted in the bottom of the oven. To properly temper the heat to effect the desired drying and curing of the envelopes with

imprints of transparentizing material I have found it desirable to supply steam through one or more jets, one of the steam jets being indicated at 230.

5. At the delivery end of the machine I provide a delivery reel 240 of grippers for taking the completely dried and cured envelopes from the chain 150 and depositing them in any suitable manner in a packing box which 10 is shown at 245. This delivery of complete envelopes may be accomplished in the manner described in my above named Patent No. 864,493.

When the envelopes are delivered in the 15 packing box 245 they are completely cured and ready for packing in boxes for delivery. The complete envelopes will be found to have a transparent window produced by the im- 20 pregnation of the material of the envelope by the imprint of transparentizing varnish. The surface of the transparent window will be smooth and glossy and there will be no danger of adjacent envelopes adhering together.

25 One of the great values of the improved machine is due to the rapidity and economy with which one-piece window envelopes can be manufactured, the drying and curing oven serving the dual purpose of drying the adhesive used in the manufacture of the envelopes and curing the transparentizing varnish which produces the window.

I believe I am the first to provide a machine for forming one-piece window envelopes by a continuous process from a roll 35 of envelope material whereby the advantages in time and cost of manufacture result.

The specific gearing and driving mechanisms for the various parts of the machine have not been described in detail since it will be obvious to anyone skilled in the art how best to arrange the various driving 45 gears to produce the desired results. The machine illustrated in the drawings is presented as one form of mechanism embodying the described invention, but it should be understood that it is not intended to limit the invention to this specific form of machine, but to cover all equivalent mechanisms known in the art for accomplishing the results described within the scope of the 50 claims annexed hereto.

I claim:

55 1. In a machine for making one-piece window envelopes, the combination of means for continuously advancing a web of envelope material, means for imprinting spaced patches of transparentizing material upon the running web, and means for forming envelopes from said web, with a drying and curing oven having an envelope conveyor passing through it.

60 2. In a machine for making one-piece window envelopes, the combination of means

for continuously advancing a web of envelope material, means for imprinting spaced patches of transparentizing material upon the running web, and rotary envelope forming mechanism, with a drying and curing oven having an envelope conveyor passing through it.

70 3. In a machine for making one-piece window envelopes, the combination of means for continuously advancing a web of envelope material, means for imprinting spaced patches of transparentizing material upon the running web, a drying and curing oven, an envelope conveyor passing through said oven, and mechanism for subdividing said running web into envelope blanks, forming envelopes from said blanks and delivering completed envelopes to said oven conveyor.

75 4. In a machine for making one-piece window envelopes, the combination of means for continuously advancing a web of envelope material, means for imprinting spaced patches of transparentizing material upon the running web, a drying and curing oven having an envelope conveyor passing through it, and rotary mechanism for subdividing said running web into envelope blanks, forming envelopes from said blanks and delivering completely formed envelopes to said oven conveyor.

80 5. In a machine for making one-piece window envelopes, the combination of means for continuously advancing a web of envelope material, means for imprinting spaced patches of transparentizing material upon the running web, means for subdividing said web into envelope blanks, mechanism for forming said blanks into envelopes, a curing and drying oven, an envelope conveyor operating in said oven, and means for transferring envelopes from said forming mechanism to said conveyor.

85 6. In a machine for making one-piece window envelopes, the combination of means for continuously advancing a web of envelope material, means for imprinting spaced patches of transparentizing material upon the running web, means for subdividing said web into envelope blanks, mechanism for forming said blanks into envelopes, a curing and drying oven, an envelope conveyor operating in said oven, means for transferring envelopes from said forming mechanism to said conveyor, and means for removing dried and cured envelopes from said conveyor.

90 7. In a machine for making one-piece window envelopes, the combination of means for continuously advancing a web of envelope material, means for imprinting spaced patches of transparentizing material upon the running web, means for applying adhesive to said web, means for subdividing said web into envelope blanks, mechanism for forming said blanks into envelopes, a

curing and drying oven, an endless chain of envelope grippers operating in said oven, means for transferring envelopes from said forming mechanism to said grippers, and 5 means for removing dried and cured envelopes from said grippers.

8. In a machine for making one-piece window envelopes, the combination of means for continuously advancing a web of envelope material, means for imprinting spaced patches of transparentizing material upon the running web, and rotary mechanisms for sub-dividing said web into envelope blanks, applying adhesive to the blank flaps, and 10 folding the blanks into envelopes, with a curing and drying oven, an envelope conveyor operating in said oven, means for transferring envelopes from said forming mechanism to said conveyor, and means for 15 removing dried and cured envelopes from 20 said conveyor.

9. In a machine for making one-piece window envelopes, the combination of continuously operating associated mechanisms for 25 advancing a web of envelope material, imprinting spaced patches of transparentizing material upon said running web, applying adhesive to parts of said running web, cutting said running web into envelope blanks, 30 and forming said blanks into completed envelopes, with a drying and curing oven having means for conveying completed envelopes therethrough for simultaneously curing the 35 imprints of transparentizing material and drying the adhesive.

10. In a machine for making one-piece window envelopes, the combination of means for continuously advancing a web of envelope material, means for imprinting spaced 40 patches of transparentizing material upon the running web, means for sub-dividing said web into envelope blanks, mechanism for forming said blanks into envelopes, a curing and drying oven, a travelling chain of envelope grippers operating in said oven and arranged to receive envelopes from said forming mechanism, means for periodically supporting the projecting sealing flap of an envelope in said grippers to hold it out of 45 contact with the next envelope passing to 50 the grippers.

11. In a machine for making one-piece window envelopes, the combination of means for continuously advancing a web of envelope material, means for imprinting spaced 55 patches of transparentizing material upon the running web, a drying and curing oven, a travelling chain of envelope grippers operating in said oven, mechanisms for applying adhesive to said running web, subdividing said running web into envelope 60 blanks, forming envelopes from said blanks and delivering completed envelopes to said grippers, and means for supporting the projecting sealing flap of an envelope in said 65

chain as a succeeding envelope is passed thereunder to the grippers.

12. In a machine for making one-piece window envelopes, the combination of means for continuously advancing a web of envelope material, means for imprinting spaced patches of transparentizing material upon the running web, mechanism for sub-dividing said web into envelope blanks, applying adhesive to the blank flaps, and forming the 70 blanks into envelopes, a curing and drying oven, a travelling chain of envelope grippers operating in said oven and arranged to receive envelopes from said forming mechanism, and intermittently operating fingers 75 movable toward and away from said chain of grippers and adapted to periodically support the projecting sealing flap of an envelope to hold it out of contact with a subsequent envelope passing into the grippers. 80

13. In a machine for making one-piece window envelopes, the combination of means for continuously advancing a web of envelope material, means for imprinting spaced patches of transparentizing material upon the running web, means for subdividing said web into envelope blanks, mechanism for forming said blanks into envelopes, a curing and drying oven, a travelling chain of envelope grippers operating in said oven and arranged to receive envelopes from said forming mechanism, and means for raising the outer corners of envelopes in the grippers and tucking the ends of the sealing flap 90 into the bite of the grippers. 95

14. In a machine for making one-piece window envelopes, the combination of means for continuously advancing a web of envelope material, means for imprinting spaced patches of transparentizing material upon the running web, means for subdividing said web into envelope blanks, mechanism for forming said blanks into envelopes, a curing and drying oven, a travelling chain of envelope grippers operating in said oven and arranged to receive envelopes from said forming mechanism, and intermittently operated fingers movable toward and away from the chain of grippers and adapted to 100 tuck the ends of the sealing flaps into the bite of the grippers. 105

15. In a machine for making one-piece window envelopes, the combination of means for continuously advancing a web of envelope material, means for imprinting spaced patches of transparentizing material upon the running web, means for subdividing said web into envelope blanks, mechanism for forming said blanks into envelopes, a curing and drying oven, a travelling chain of envelope grippers operating in said oven and arranged to receive envelopes from said forming mechanism, means adapted to periodically support the projecting sealing flap 110 of an envelope to hold it out of contact with 115 120 125 130

a subsequent envelope passing into the grippers, and means for raising the outer corners of envelopes in the grippers and tucking the ends of the sealing flap into the bite of the grippers.

16. In a machine for making one-piece window envelopes, the combination with a drying and curing oven having an envelope conveyor passing through it, means for heating said oven, and means for injecting tempering steam into said oven, of means for delivering to said oven conveyor envelopes having window forming imprints of transparentizing material.
- 10 17. In a machine for making one-piece window envelopes, the combination of means for advancing a web of envelope material,

means for imprinting spaced patches of transparentizing material upon the web, means for forming envelopes from said web, an envelope conveyor, means for delivering envelopes from the forming mechanism to said conveyor, a drying and curing oven enclosing said conveyor, means for heating said oven, and means for injecting steam into said oven.

18. In a machine for making envelopes, the combination with a drying and curing oven having an envelope conveyor passing through it, means for heating said oven, and means for injecting tempering steam into said oven, of means for delivering envelopes to said oven conveyor.

GEORGE W. SWIFT, JR.
